LEVER OPERATED COLLET CHUCK HEAD

Donald J. Behnk, Allison Park, Pa., and Donald M. Streiff, Kettering, Ohio, assignors to The Jacobs Manufacturing Company, West Hartford, Conn., a corporation of New Jersey

Filed Dec. 11, 1964, Ser. No. 82,993

Term of patent 14 years

(Cl. D54—6)

FIG. 1

FIG. 2

FIG. 3

FIG. 4

FIG. 1 is a front perspective view of a lever operated collet chuck head, showing our new design;

FIG. 2 is a front perspective view thereof, as seen from the top and right side;

FIG. 3 is a bottom plan view thereof; and

FIG. 4 is a rear elevational view.

In FIGS. 1, 3 and 4, the lever member is fragmentarily shown for convenience of illustration. The solid black and stippled areas in FIGS. 1, 2 and 4 are shown for purposes of contrast.

The broken line showing of the machine adapter elements are disclosed for illustrative purposes only.

This application is a continuation-in-part of our design application, Serial Number D. 74,508 filed April 18, 1963, and abandoned subsequent to the filing of this application.

We claim:

The ornamental design for a lever operated collet chuck head, as shown and described.
